UNITED STATES PATENT OFFICE.

RUSSELL EDWARD LUNDAY, OF HURLEY, NEW MEXICO.

COLLAPSIBLE SHOEHORN.

Application filed October 22, 1926. Serial No. 143,424.

My invention relates to improvements in shoe horns of the collapsible type, and it consists in the combinations, constructions, and arrangements herein described and claimed.

An object of my invention is to provide a shoe horn which not only can be collapsed longitudinally to shorten it, but which also may be collapsed laterally, so as to provide a device which, when collapsed, is in a very compact form not larger than the ordinary key, and which, therefore, may be carried conveniently in the pocket.

A further object of the invention is to provide a device of the type mentioned, which may be readily manipulated so as to expand it or collapse it at will.

Other objects and advantages will appear in the following specification, and the novel features of the invention will be particularly pointed out in the appended claims.

My invention is illustrated in the accompanying drawings, forming part of this application, in which

Figure 1 is a face view of a blank which forms the casing,

Figures 2, 3 and 4 are face views of the movable parts,

Figures 5 and 6 are sectional views of the members shown in Figures 2 and 4, respectively;

Figure 7 is a view of the device showing it in its expanded position.

Figure 8 is a face view, showing the device collapsed,

Figure 9 is a sectional view along the line 9-9 of Figure 8;

Figure 10 is a longitudinal sectional view through the casing, showing the relation of the movable parts,

Figure 11 is an edge view of the device in its collapsed condition, and

Figure 12 is a sectional view along the line 12-12 of Figure 7, showing the relation of the movable parts in their expanded condition.

In carrying out my invention, I provide a main body portion which consists of a stamping similar to that in Figure 1. This is preferably made of sheet metal. It will be observed that this stamping has two contiguous loop portions 1 and 2, respectively, which may be folded together on the dotted line 3 so as to register. The loop portion 1 has an integral extension 4 of the shape shown, there being a groove 5 impressed in the member 4 and extending diagonally

from the loop portion to the outer end. An integral ear 6 is provided, as shown.

The loop portion 2 has an integral extension 7, similar to the extension 4, a groove 8 running diagonally, and an ear 9, similar to the ear 6. It will be observed that both the portions 4 and 7 have their edges on one side; i. e., the right-hand side in Figure 1, cut partially away, as shown at 10.

The portions 4 and 7 are bent at right angles on the dotted lines 11 toward the grooved side, and then the blank is bent at 3 so that the portions on each side of the line are brought into registration. The ears 6 and 7 are then bent around the opposing portion, thus forming a casing having the grooves 5 and 8 crossing one another.

In Figures 2 and 5 I have shown at 12 one of the outer movable elements. This has a rolled or beaded outer edge 12^a, while in Figures 4 and 6 a similar element 13 is disclosed with a bead 13^a on its outer edge. Both of these elements 12 and 13 taper, as shown in the drawings. The element 12 is provided with a laterally extending portion 12^b at one end; see Figure 5, while the companion member 13 has a hook-like extension 13^b.

In Figure 3 I have shown a central member 14 which consists of a flat plate having at its lower end laterally extending slots 15 and 16, respectively. It is also provided with an ear 17, which extends laterally and is bent back upon itself to provide a handle member for moving the parts, as will be explained later. Each of the parts 4, 7, 12, 13 and 14 is curved on an arc so that when the parts are assembled they can be nested in the manner shown in Figures 9 and 12.

In assembling the device, the member 12 is placed on one side of the member 14 with the lug or extension 12^b passing through the slot 15. The other member 13 is placed on the opposite side with its hook 13^b extending through the slot 16. The arrangement is such, that, when the movable members are enclosed within the casing formed by bending together the parts shown in Figure 1, the beads 12^a and 13^a will enter the grooves 5 and 8, respectively, while the handle portion 17 will extend through the slots 10^a, see Figure 11, formed by the cutaway portions 10 and when the device is in its collapsed position, the lugs 12^b and 13^b will be toward opposite ends of their respective slots 15 and 16.

From the foregoing description of the various parts of the device, the operation thereof may be readily understood. Let us assume that the device is in its collapsed condition, as shown in Figure 11. Now, by pressing the handle portion 17 upwardly in Figure 11, the central member 14 will be moved out of the casing. This will cause an outward movement of the side members 12 and 13. The latter, however, are guided in their movement by the fact that their beads 12^a and 13^a are in the grooves 5 and 8. Therefore, these members will have a lateral movement as well as a longitudinal movement, as the handle 17 is moved. Since these members are curved, there will be a sliding movement of the outer members with respect to the central member, so that when the device is expanded, it will take the arc shape, shown in Figure 12; i. e., it will be expanded into the shape of the ordinary shoe horn. In order to prevent the edges on the concave side of the expanded horn from cutting the stocking, they are tapered off. It will also be observed that the slot 10^a is brought to a taper at its ends. When the handle 17 is at either end, it is held frictionally by the narrow portion of the slot, thus virtually clamping the parts either in their collapsed or expanded positions.

It will be noted that I have provided a shoe horn having a handle portion which serves as a casing, and a blade portion made up of movable parts which can be projected from the handle portion, the blade being expanded as it emerges.

The collapsing or expanding of the device may be accomplished very quickly, and, when the movable parts are brought within the casing, it takes up very little room, in fact not more than an ordinary key, and can, therefore, be carried on a key chain in the pocket and be always handy.

It will be understood that the proportions or parts are not those shown in the drawing. As a matter of fact, the casing and the movable members are made of relatively thin metal. In order to show the relation of the beads and grooves, however, it was necessary to exaggerate the thickness of the metal so that Figure 9, which is a section of the assembled parts, shows these parts relatively thicker than they are in actual practice.

I am aware that collapsible shoe horns are not broadly new. The horns with which I am familiar, however, collapse longitudinally, but not laterally. The importance of collapsing them laterally lies in the fact that it brings them into a compact form which can be carried on a key chain with other keys, whereas a shoe horn collapsible longitudinally only would be too bulky to carry in this manner.

When the device is expanded, it is used in the ordinary manner and facilitates the putting on of shoes.

I claim:

1. A shoe horn, comprising a handle portion and a blade portion movable into and out of one end of said handle portion, and means for causing the expansion of the blade laterally during the outward movement. 70

2. A shoe horn, comprising a handle portion and a blade portion movable into and out of one end of said handle portion, and means for causing the expansion of the blade laterally during the outward movement and for causing the collapsing of the blade during the inward movement. 80

3. A shoe horn, comprising a casing having guide grooves therein, a blade movable into and out of one end of said casing, said blade having a central portion and laterally movable side portions, and means carried by the side portions for engaging the guide grooves within the casing. 85

4. A shoe horn, comprising a hollow handle portion having a longitudinal slot, said handle portion being open at one end and closed at the other, a blade movable into and out of the open end, said blade having a central member provided with an extension arranged to pass through said slot, and a pair of laterally movable members slidably secured to said central member. 90

5. A shoe horn, comprising a hollow handle portion having a longitudinal slot, said handle portion being open at one end and closed at the other, a blade movable into and out of the open end, said blade having a central member provided with an extension arranged to pass through said slot, a pair of laterally movable members slidably secured to said central member, and means carried by the handle and arranged to engage said side members for causing a lateral movement of the side members with respect to the central member. 105

6. A shoe horn, comprising a metal casing provided with a longitudinal slot and having oppositely extending guide grooves in the walls thereof, a blade movable into and out of said casing, said blade comprising a central member having transverse slots, side members having lugs arranged to slide in said slots and being provided with beads arranged to enter said grooves in the casing, and an integral handle member carried by said central member for moving the latter into and out of said casing. 115

7. A shoe horn, comprising a hollow handle having opposed arc-shaped walls, said walls being provided with oppositely extending grooves, a blade portion movable into and out of said handle, said blade portion comprising a central strip bent in arc shape and being provided with a pair of 125

slots near one end thereof, arc-shaped side members having lugs at the ends thereof arranged to enter certain of said slots in said central member, each of said side members having a bead on its outer edge arranged to enter one of the grooves in said handle member, and an integral extension

carried by said central member and arranged to project exteriorly of said handle, whereby said central member may be moved ¹⁰ into and out of said handle together with said side members.

RUSSELL E. LUNDAY.
